TOY WALKIE TALKIE

Felix Gilbert, New York, N.Y., assignor to De Luxe Reading Corporation, Elizabeth, N.J., a corporation of New Jersey

Filed Apr. 23, 1964, Ser. No. 79,729

Term of patent 14 years

(Cl. D34—15)

FIG - 3

The essential features of my design reside in the portions shown in full lines, the broken line showing of the antenna being seen fragmentarily for convenience of illustration.

I claim:

The ornamental design for a toy walkie talkie, substantially as shown and described.
